ATTORNEY

UNITED STATES PATENT OFFICE

MILDRED A. KOLAR, OF PORTLAND, OREGON

DOLL

Application filed February 17, 1930. Serial No. 429,030.

This invention relates generally to toys, and particularly to dolls.

The main object of this invention is to provide a doll having a heating appliance associated therewith, especially adapted for use in a child's bed for the purpose of giving the child the benefit of the heat and the pleasure of the companionship of the doll.

The second object is to so construct the doll that it readily adapts itself to use in connection with the ordinary hot water bottle.

The third object is to so construct the doll that it can be easily manufactured and washed and that the hot water bottle, electric heating pad, or other device can be employed without any difficulty.

The fourth object is to protect the stuffed portions of the doll with a water-proof covering.

The fifth object is to so disguise a hot water bottle, or other heating device, as to overcome any objection in the child's mind and to cause same to hold the heating appliance close to its body.

The sixth object is to so construct the doll that the heating appliance when not required can, if it is a hot water bottle, be inflated with air, or if some other contrivance can be substituted by a pad or other suitable filler.

These, and other objects, will become more apparent from the specification following as illustrated in the accompanying drawings, in which:

Figure 1 is a front elevation of the doll.

Figure 2 is a rear elevation of the doll.

Figure 3 is a fragmentary section along the line 3—3 in Fig. 2.

Figure 4 is a front elevation of the doll dressed in night clothing.

Figure 5 is a side elevation of Fig. 4.

Figure 6 is a section taken along the line 6—6 in Fig. 2.

Figure 7 is a side elevation of the stopper for the hot water bottle.

Similar numbers of reference refer to similar parts throughout the several views.

Referring in detail to the drawings, the doll consists of a somewhat rectangular body member 10 which is hollow and preferably made of a water-proof material having a flannel lining 11 provided with a closing flap 12 at one end thereof to which is attached a pair of legs 13, also covered with water-proof material. The flap 12 may be secured to a closed position by means of the snaps 14. At the top of the body member 10 are secured the stuffed arms 15 and the neck 16 of a head 17. The arms, neck and head are all permanently stuffed and covered with water-proof material.

Within the body 10 is placed an ordinary hot water bag 18 whose stopper 19 is provided with a flexible hose 20 ordinarily folded over and secured by means of a rubber band 21, similar to the filler tube on a foot-ball or basket-ball. When it is not desired to use the hot water bag within the doll the water is removed and the bottle is inflated through the tube 20 providing the desirable roundness for the body 10 and holding the sides of the bag out of contact with each other, thereby adding to the life thereof.

It will be understood that the stuffing material 22 may be of any convenient material.

The doll thus described is preferably dressed in a sleeping garment 23 made of flannel or other suitable material of a washable nature. The details of construction of this garment and of the doll itself are of secondary importance, in view of the fact that the same principle may be employed with animals such as bears, dogs, elephants, etc. without departing from the spirit of this invention. The particular form illustrated and described has been selected merely as a matter of convenience.

It will be understood that while there is illustrated the use of a standard hot water bottle it is also possible to construct the en-

tire body of the doll, including the legs, arms and head, of rubber instead of employing the standard hot water bottle, and then dressing the body thus formed with clothing as above suggested.

5 I claim:

A doll consisting of a casing in the form of a doll's body, said casing consisting of a material adapted to retard the flow of heat therefrom and having an opening therein through which a hot water bottle may be passed, a hot water bottle occupying the torso of said body, and means in the closure of said bottle for inflating same when not filled with water.
